Kenneth E. Moyer, Port Vue, Pa., assignor to
Bernard N. Cantor and Educational Toy Insti-
tute of New York, both of Staten Island, N. Y.

Application April 8, 1952, Serial No. 19,239

Term of patent 14 years

(Cl. D25—1)

To all whom it may concern:

Be it known that I, Kenneth E. Moyer, a citizen of the United States of America, residing in Port Vue, the county of Allegheny, State of Pennsylvania, have invented a new, original, and ornamental Design for an Educational Toy Vehicle, of which the following is a specification, reference being had to the accompanying drawing, forming a part thereof.

In the drawing:

Fig. 1 is a perspective view of an educational toy vehicle with four of the load blocks removed.

Fig. 2 is an elevational side view of the educational toy vehicle, showing my new design, and

Fig. 3 is a plan view of the educational toy vehicle shown in Fig. 2.

I claim:

The ornamental design for an educational toy vehicle, as shown.

KENNETH E. MOYER.
